UNITED STATES PATENT OFFICE

ERI H. RICHARDSON, OF SAN MATEO, CALIFORNIA

FIREPLACE

Application filed May 8, 1926. Serial No. 107,668.

The present invention relates to fireplaces for rooms, apartments and the like, and a primary object of the invention is to provide a fireplace designed to furnish the maximum amount of heat with the expenditure of the least amount of fuel, and which will certainly carry off the products of combustion under normal conditions without leakage into the room or apartment.

I have discovered that this object can be attained by observing certain relations and following certain rules in the arrangement and proportioning of the hood and throat parts of the fireplace, the design of the smoke chamber, the width of the hood and soffit and the extent to which the fireback should be carried above the soffit to provide a hood. These matters are equally as important as the provision of a chimney flue of correct size. Yet, so far as I am aware, little attention has been paid in fireplaces constructed before my invention to any of the features that I have found to be of primary importance to the production of an efficient fireplace, both from the standpoint of economy in fuel and satisfactory operation and results. It is another object of the invention to provide a novel method of constructing fireplaces in which a damper supporting structure is utilized which is so designed that it may be used as a templet or guide by persons not versed in the essentials of a correctly functioning fireplace, to produce a construction that meets the requirements of an efficient fireplace.

This invention I believe to be entirely novel in producing a construction in which certain of the essential fireplace and throat parts are proportioned to the height of the fireplace opening.

I have found as the result of extensive experience, both in designing and building fireplaces and in repairing many hundreds of faulty fireplaces that in order to give the greatest practical protection against smoking or back puffing and at the same time project into the room the greatest amount of heat, that it is necessary to observe a relation or proportion between the height of the fire place opening and the

width of throat aperture; height of fireback, height of front plate or hood and depth of fireplace on the level of the top of opening or soffit.

It has been common practice heretofore to furnish fireplaces or parts or dampers of various constructions to meet given lengths (or widths) of fireplace openings, the parts being elongated or enlarged or made heavier to meet the requirements of length. Under 55 the existing practice no attention has been paid to an increased or diminished height of fireplace opening, the parts of the hood, throat or damper being fixed without regard or consideration for the varying heights. 60 Such hood, throat, or damper would be furnished with the same relation of parts regardless of whether the fireplace opening were 2' or 4' or of any other height. This common construction I claim to be not only 65 wasteful of heat but often improperly constructed to give satisfactory results. I have determined it to be a fact that often the fireplace which smokes the least is so openly constructed in the throat parts as to be most 70 wasteful of heat and a producer of draughts which are at times more objectionable than 75 lack of heat.

Further objects will appear as the description proceeds with references to the accompanying drawings in which,

Figure 1 is a front elevation of a fireplace constructed according to my invention.

Figure 2 is a central vertical section on the plane, indicated by the line A—A of 85 Figure 1.

Figure 3 is a detail showing the damper blade in front elevation.

Figure 4 is a top view of the blade.

Figure 5 is a vertical sectional view on an enlarged scale, through the damper assembly, showing the left end plate.

Figure 6 is a section on the line B—B of 95 Figure 5.

Figure 7 is a detail view showing the damper blade in end elevation on an enlarged scale, a portion of said blade being broken away to show the connection of the damper handle.

Figures 8 and 9 are vertical and horizontal sections of a modification.

The same reference numerals indicate like parts in the several figures.

5 1 is the hearth of the fireplace in the wall of the room that has an opening bounded by hearth 1, side walls 2 and 3, and soffit 4. As shown on Figures 1 and 2 of the drawings side walls 2 and 3 are straight. If 10 desired the fireplace may be constructed as shown in Figures 8 and 9 in which the side walls 2 and 3 are straight only for a portion of the depth, and inclined for the remainder of the depth of the fireplace. The width of 15 the back in a fireplace having inclined sides is, preferably, one-half the width of the opening though this may be varied 15% either way without interfering with the satisfactory operation of such a fireplace.

20 In general the depth of the fireplace in both forms of my invention should be made, at least, one-third of the width of the opening and preferably is made one-half the width of the opening for the safest and most practical construction. A depth of less than 25 18 inches is not likely to be sufficient except for small grate fires, and a depth of more than 30 inches is likely to be wasteful of heat. Fireback 5 is preferably curved forwardly toward the opening as shown in 30 Figures 2, 8 and 9 and extends upwardly to a point 6, a distance vertically above the soffit, preferably equal to 25 percent of the height of the fire place opening, though satisfactory operation may be obtained if this 35 distance is 15 to 30 percent of the height of the opening. Preferably the depth of the fireplace is measured about 8 inches above the hearth level, but may be determined at 40 said level.

The modified form of my invention including the inclined sides 2' and 3' are preferable from the architectural standpoint, giving the fireplace the appearance of stability and 45 functioning to reflect more of the heat from the sides into the room.

Curved fireback 5 is made slightly concave to form an arch providing a construction that is capable of resisting the expansion and contraction of the fireback without 50 causing disintegration of the material of which said back is constructed. Preferably, the curve of said back is determined by a radius equal to twice the opening height, 55 though I do not wish to be limited to such specific curvature since variations thereof will obtain all of the advantages of my improved curved fireback.

The soffit 4 should be narrow, preferably 60 about one and one-half inches in width, and inner wall 7 of the fireplace above the soffit extends upwardly and inwardly preferably though not necessarily at an angle of about 60°, and is so formed as to provide with the 65 upper edge 6 of the fireback a throat 8.

Fireback 5 and wall 7 extend the full width of the fireplace, forming between them a hood 9. This is accomplished in the modified form of my invention shown in Figures 8 and 9 by discontinuing the slanting sides 2' and 3' at the top of the fireplace opening, 70 making the hood from this point upwardly equal to the full width of the opening. It is important to the attainment of high efficiency that the length of throat 8 and hood 9 be of the full width of the fire place opening, as shown on the drawings, giving ample space for the collection of gases which are retarded from too ready escape by narrow throat 8.

75 This full width of the hood 9 is maintained to a height above the soffit equal to, at least, 20 percent and not more than 40 percent of the height of the fireplace opening. The products of combustion are collected by the hood 9 and pass through the throat 8 into a smoke chamber 10 that is of the full width of the opening to a point or level 11, where the inward taper toward a flue 12 of the chimney begins. By maintaining the length 80 of throat and hood equal to the full width of the opening and continuing such undiminished width into the smoke chamber, a spacious chamber is provided reducing thereby the likelihood of puffing or down draughts. The throat 8 leading into the smoke chamber 10 is preferably of a width equal to 10 percent of the height of the opening of the fireplace, though a width between 8 percent and 15 percent of said 85 height will operate satisfactorily. The flue 12 leading to the chimney has preferably, a cross sectional area that is about 10 percent of the area of the chimney opening. A cylindrical flue may be used, permitting a 90 natural whirling motion of the smoke and gases. By the arrangement of a spacious smoke chamber between flue and throat, smoke will be hampered from entering the room when a gust of wind coming down the chimney opposes the ready egress of said 95 smoke, since in this event the force of the current of air tending to force the smoke into the room will be somewhat or entirely 100 dissipated in the smoke chamber.

105 I have found that by proportioning the throat and flue as above described with relation to the fireplace opening, a construction is provided in which the outlet from the fireplace is ample to take care of the products of combustion without being too large and causing a waste of fuel. And when an outlet so proportioned is combined with fireback of proper depth and curve, a hood, collecting said products, that has its outer edge 110 spaced from the plane of the adjacent outer surface of the wall by a narrow soffit of a width of about one and one-half inches, a construction is provided that I have found to be of high efficiency in every respect.

In order that a fireplace having the above characteristics may be built by persons that are not versed in the essential elements of a correctly functioning fireplace, I provide a 5 damper supporting construction that is adaptable to fire places having openings of varying heights and widths and that is so constructed that a correctly designed fireplace is produced when the fireplace is constructed around my improved damper supporting construction. That is, the width and length of throat 8, the height and depth of hood 9, the height of fireback 5, the width of soffit 4 and the inclination of inner 10 wall 7 are all determined from my improved damper supporting construction. In addition the pivotal point of the damper is located by said construction. As the damper supporting construction is designed with regard to the height of the fireplace opening, 15 all of the elements above specified will be determined in terms of said fireplace opening height. My improved damper supporting construction will serve as a templet for 20 a properly designed fireplace and also serve as a support for a damper, when one is used.

My damper construction and templet comprises two end plates 13 and 14 that are 25 duplicates, except that one is the reverse of the other. Each plate has a flange 15 and a reversely bent portion 16 forming a channel to receive the edge of a top plate 17 (Figure 6). Flange 15 and channel 16 are im- 30 bedded in the side walls of the fireplace. The front plate 17 forming a part of hood 9 is inserted endwise into channels 16 and is secured to the end plates by bolts 18. Plate 17 has a horizontally extending flange 35 40 19 that is of a length equal to the width of the soffit in a correctly proportioned fireplace.

In order to permit lateral or horizontal 45 expansion of the top plate 17 the openings 17^a that receive the bolts are enlarged and plate 17 terminates short of the bottom of channel 16 as shown at 17^a. This construction permits the movement of the plate 17 due to changes in its temperature without 50 causing cracks or fissures in the adjacent masonry. Vertical expansion and contraction of the top or front plate may be taken care of, if essential, by constructing the same in sections attached together by fasteners of any kind that pass through overlying elongated holes formed in lapping portions of said sections, or by providing clearance between the ends of the front plate and the end plates or walls of the fireplace, or in any other suitable manner. In this way cracking of the fireplace above the opening will be avoided.

Arranged in each of the end plates 13 and 14 are two series of spaced perforations 55 20 and 21, in any corresponding ones of which

integral pintles 22 of a damper blade 23 may be arranged. Damper blade 23 is preferably provided with a laterally extending flange 24 that has perforations 25 to receive the eye 26 of a damper operating lever 27 (Figures 2 and 7) which passes through a guiding and supporting clip 28 and has an ornamental handle 29 at its end. Stop projections 29' may be formed on the end plates 13 (Figure 5) against which the 70 damper blade 23 is adapted to rest in open position. It will be noted that this handle does not project through the wall surrounding the opening of the fireplace. The handle is held in adjusted position by the 75 engagement of one of the teeth 30 with guiding clip 28 or by any other means.

The series of pintle receiving openings or bearings 20 and 21 are so located in the end plates 13 and 14 that properly aligned pairs of supporting openings for the ends of the damper pintle 22 are provided which also mark the top edge of the fireback 5 for correctly proportioned fireplaces of various heights of openings. The opening height 80 corresponding to each hole is preferably stamped in inches on the plates 13 and 14 and indicated by the numerals 24", 26", 28", etc. below the respective openings. Said holes indicate the point to which the 85 fireback is properly carried for the various heights of fireplace openings without regard to whether a damper is used.

It will be obvious that any suitable means other than holes may be used to serve as a 90 substitute arrangement for said holes. For example, a series of projecting bearings of any type may be substituted, my invention being in no way limited to the use of series of holes as a means to serve as a guiding point in the construction of a properly designed fireplace or as a pivotal means for the damper pintles.

Rib 24 is reduced in width at 32. It is the purpose of this rib to conserve the heat 100 at the points farthest removed from the greatest volume of smoke. Front plates 17 and damper blades 23 may be furnished in various lengths corresponding to the desired lengths of the fireplace openings and the 105 damper blades are of supplied widths that will be sufficient to bridge the space between the selected pintle support and the opposite surface of the throat 8.

When constructing a fireplace in accordance with my improved method, the damper assembly adapted for the particular size of fireplace desired is preferably used as a templet to secure the proper fireplace proportions. The top plate forms a proper 115 hood and a narrow soffit of correct width. The fireplace side walls are built to give the desired width of opening, and the damper side plates with the damper pintles in the holes corresponding to the chosen height, 120 125 130

are embedded in the side walls with their lower edges spaced from the hearth of the fireplace a distance above the opening to complete an ample hood and give correct height of fireback. The fireback is then brought up to the lower edge of the damper. The plate 17 may be placed in position either before or after the end plates 13 and 14 are embedded in the side walls and the front wall is constructed with reference thereto and of a thickness at its lower edge corresponding to the width of flange 19 of the top plate. The full width of opening is maintained in the construction of the smoke chamber to the level indicated by the upper corner 33 (Figure 2) of plates 13 and 14. From this point the walls of the smoke chamber converge to the chimney flue 12. The remaining proportions of the fireplace are readily constructed from this point on in accordance with a few simple directions which are preferably supplied with the damper assembly, giving the proportions as above set forth for the flue connection and remaining parts of fireplace for the various size openings for which the damper assembly is designed.

It will accordingly be seen that an ordinary mechanic can readily build a properly proportioned fireplace structure in accordance with my improved invention by the use of my combined hood, throat and damper construction as a template or guide for its construction.

It will be understood that instead of having a separate top plate 17, the top plate 17 and the side walls 13 and 14 may be formed integrally and constructed from a single metal sheet or molded composition. It will also be understood that the damper blade may be bent from a single metal sheet with projecting ends bent to form the supporting pintles or pivot points therefor.

While the preferred way of constructing my improved fireplaces in accordance with my invention is to use the combined damper, hood and throat construction as a template or guide, it will be obvious that a fireplace constructed in any well known manner may be proportioned in accordance with my invention. The damper blade may be omitted, if desired, as shown in Figure 8. It will therefore be understood that the invention is not restricted to the details hereinbefore set forth but that the scope thereof is to be determined from the terms of the appended claims. Accordingly,

What is desired to be secured by Letters Patent and claimed as new is:

1. A fireplace including a narrow soffit, a fireback extending a substantial distance above said soffit but spaced therefrom to form a hood, a smoke chamber, a flue, a throat of restricted width but of a length equal to the full width of the fireplace open-

ing leading from said hood to said smoke chamber, the smoke chamber being of the full width of the fireplace opening adjacent the throat and gradually converging to said flue, said flue and said throat being of substantially the same cross sectional area. 70

2. A fireplace including a fire back that is carried a substantial distance above the upper edge of the opening to form a smoke collecting hood, a throat of restricted area 75 extending from said hood, a smoke chamber above said throat and communicating therewith, said smoke chamber being of relatively large capacity, and a chimney flue connected to said smoke chamber, the cross sectional area of said flue being substantially 80 the same as the cross sectional area of said throat.

3. A fireplace including a throat, a smoke chamber and a flue of a cross sectional area 85 substantially the same as said throat, said smoke chamber being between said throat and said flue, said throat and each flue being of restricted area compared to the fireplace opening, the smoke chamber being of the 90 full width of said opening through a substantial portion of its height and tapering thereafter to the size of the flue.

4. A fireplace including a fireback extending 15 to 30 per cent of the height of the 95 fireplace opening above said opening, a throat of the full width of said opening and with an aperture equal to of from 8 to 15 percent of its height leading therefrom, a smoke chamber communicating therewith, 100 and a chimney flue in communication with said smoke chamber, said flue having a cross sectional area corresponding substantially to the cross sectional area of said throat.

5. A fireplace as defined in claim 4 in 105 which the smoke chamber is of the full width of the fireplace opening throughout a substantial portion of its height and tapering thereafter to the size of the flue.

6. A combined fireplace templet and damper support comprising a plate provided with means to attach it to an end wall of the fireplace, means on said plate to predetermine the contour of the inner surface of the front wall of the fireplace, and means 110 on said plate to indicate the point to which the fireback of the fireplace should be carried, and to support the damper.

7. A combined fireplace templet and damper support comprising a plate provided 115 with means to attach it to an end wall of the fireplace, bearing means formed on the edge of said plate conforming to the inner surface of the front wall of the fireplace, and means on said plate to indicate the 12 point to which the fireback should be extended, said last named means being constructed to serve as the pivotal support for the damper.

8. A fireplace templet and damper sup- 120

port as defined in claim 7, in which the damper supporting means are a plurality of holes arranged in series spaced differing distances from the securing means.

5 9. A combined fireplace templet and damper support comprising end plates having their edges shaped to conform to the under surface of the front wall of said fireplace, a plate secured to said plates projecting forwardly of the edge of said end plates a distance equal to the desired soffit of the fireplace, and means on said end plates to indicate the extent of the fireback for openings of various sizes, said last named means serving to support the damper.

10 10. A construction as defined in claim 9 in which the damper supporting means comprises series of holes differently spaced with respect to the upper edges of the end plates and in which the holes carry adjacent indicia showing the position of the damper for openings of various heights.

15 11. A fire place including a hood comprising a pair of end members positioned in the side walls of the fireplace above the opening, and a member extending transversely of the fireplace between said end members, said transversely extending member defining the width of the soffit and the front of the hood and said side members being provided with indicia to indicate the extent of the fireback and the width of the throat leading from said hood to the smoke chamber, said end plates being provided with a plurality of dampers supports associated with the various indicia to support the damper in proper position for the width of the throat and height of the fireback.

20 12. A fireplace including a hood comprising a pair of end members positioned in the side walls of the fireplace above the open end, a member extending transversely of the fireplace between said end members, said transversely extending member defining the width of the soffit and the front of the hood, and said side members being provided with indicia in terms of height of fireplace opening to indicate the extent of the fireback constituting the rear of the hood and to show the correct width of the throat leading to the smoke chamber, said end plates being provided with a plurality of damper supports associated with the various indicia to support the damper in proper position for the width of the throat and height of the fireplace.

25 13. A fireplace consisting of smoke collecting and discharging portions built about a combined hood and templet, said hood and templet comprising sheet metal transverse and longitudinal members secured together to form a lining for said discharging portion, said transverse members being provided with a plurality of damper supports arranged in position to give efficient opera-

tion for various heights of fireplace openings and indicia adjacent said support to show the proper location of the damper for each of said heights.

In testimony whereof I affix my signature. 70
ERI H. RICHARDSON.
